TELEVISION MAST FREEZE GROMMET

Barto Sampo, Cherry, Ill.

Application June 13, 1955, Serial No. 514,950

2 Claims. (Cl. 288—19)

This invention relates to a device for use in conjunction with a television mast so as to prevent moisture and other foreign matter from entering the space between the television aerial mast and the top bushing of the television tower which might otherwise freeze so as to not only prevent the rotation of the mast within the tower bushing but which may cause serious deterioration of the antenna arrangement.

The primary object of the present invention resides in the provision of an easily installed means for sealing the connection between a television antenna mast and a top bushing of a television aerial tower.

A further object of the invention resides in the provision of an easily installed grommet which will seal the connection between two different members in a novel manner.

The construction of this invention features the utilization of a grommet which may be formed in sections and which includes cylindrical portions having larger inner diameters than conical portions. The grommet is preferably formed of a suitable resilient material and may be easily detachably installed in position, as may be desired.

Still further objects and features of this invention reside in the provision of a television mast freeze grommet that is simple in construction, highly efficient in use, which can be easily manufactured at relatively low cost, and which is capable of being manufactured in various sizes.

These, together with the various ancillary objects and features of the invention which will become apparent as the following description proceeds, are attained by these television mast freeze grommets, preferred embodiments of which have been illustrated in the accompanying drawings, by way of example only, wherein:

Figure 1 is a perspective view of a unitary form of television mast freeze grommet;

Figure 2 is a vertical sectional detail view taken along the plane containing the axis of the grommet;

Figure 3 is an exploded perspective view of a modified form of television mast freeze grommet having a pair of sections;

Figure 4 is a vertical sectional view illustrating the construction of the modified form of television mast freeze grommet; and

Figure 5 is an enlarged sectional detail view as taken along the plane of line 5—5 in Figure 4.

With continuing reference to the accompanying drawings wherein like reference numerals designate similar parts throughout the various views, and with initial attention directed to the embodiment of the invention as is shown in Figures 1 and 2, reference numeral 10 is used to generally designate the television mast freeze grommet which is adapted to be positioned about the television aerial mast 12 and the bushing 14 of the television tower. The grommet 10 includes a substantially hollow cylindrical portion 16 which has integrally formed therewith a truncated conical portion 18 having a bore 20 there-

2

through receiving the mast 12. The cylindrical portion 16 is hollow and the inner side walls 22 thereof engage the bushing 14. In this manner, a highly effective seal is achieved. It is noted that the diameter of the bore 20 is considerably less than the diameter of the recess receiving the bushing 14.

The grommet 10 may be formed of any suitable material, such as rubber, neoprene or the like, and seals the joint against penetration by moisture or other foreign matter. This enables the mast 12 to be readily rotated relative to the bushing 14.

In Figures 3, 4 and 5, there is shown a modified form of the invention in which the grommet 30 is formed of a pair of grommet sections 32 and 34. The grommet sections 32 and 34 each have substantially semicylindrical portions 36 and 38 which are hollow for reception of the bushing 40. Likewise, the semitruncated conical sections 42 and 44 have a bore 46 therethrough of lesser diameter than that of the opening receiving the bushing 40 for reception of the mast 48.

The sections 32 and 34 are each formed with end walls 50, 52 and 54, 56, respectively. The end walls 50 and 52 have suitable tongues 58 and 60 integrally formed therewith which are adapted to seat within recesses 62 and 64 in the end walls 56 and 54. Rows of projections 66 and 68 are integrally formed with the tongues 58 and 60 and adapted to seat within recesses arranged in rows, as at 70 and 72. The projections, as can be best seen in Figure 5, each includes a stem portion 76 having a semispherical head portion 78 thereon. This forms a highly effective interlock since the projections are formed of the same resilient material as the main portions of the grommet.

In use, with the antenna already installed, it is a simple matter to install the television mast freeze grommet 30 by merely positioning the sections of the grommet in place and then squeezing them together. This forms a highly effective seal against the penetration by moisture or foreign matter.

If water or other foreign matter enters the space between a television aerial mast and the top bushing of a tower and the water freezes and immobilizes the antenna or the antenna is immobilized in some other fashion, either the rotor motor which turns the antenna or the rotor motor control becomes shorted and burns out when an attempt is made to turn the antenna. In all areas removed from television stations, it is necessary to turn the antenna in the direction of the signal in order to receive a picture. Such an installation causing the antenna to turn when desired is costly and if it is caused to burn out due to something between the mast and bushing, an installation with a similar cost is necessary. Thus, the present invention provides protection to the installation and maintains it continuously available.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A television mast grommet comprising a pair of grommet sections made of resilient material, each of said sections having a hollow semi-cylindrical portion and an integrally connected truncated semi-conical portion, said semi-cylindrical portions having a bore, said truncated semi-conical portions having a bore coaxial with the bore of said semi-cylindrical portion and of a smaller diameter, said coaxial axes constituting a longitudinal central axis of the grommet sections, said sections having

pairs of abutting longitudinal walls with parts thereof parallel to said central axis, the walls of one of said sections having longitudinally extending tongues thereon with parts of said tongues parallel to said central axis, the walls of the other of said sections having longitudinally extending grooves therein with parts of said grooves parallel to said central axis, projections on said tongues, said projections having stems and enlarged heads at the outer ends of said stems, said walls with said grooves having recesses which communicate with said grooves, said stems and heads of said projections interlocking in said recesses and said tongues seated in said grooves to hold said sections fastened together.

2. The television mast grommet of claim 1 wherein there are parts of said tongues and grooves on said abutting longitudinal walls which are inclined inwardly towards said central axis, the inclined parts of said tongues and grooves being on said truncated semi-conical portions of said sections.
